GRAINING MACHINE

Herbert J. Pattison, Detroit, Mich., assignor to
 Briggs Manufacturing Company, Detroit, Mich.,
 a corporation of Michigan

Application March 22, 1939, Serial No. 263,497

16 Claims. (Cl. 271—12)

This invention relates to graining machines and a method for applying ornamental patterns to the surfaces of flat articles such as metal plates, sheets or panels to be used, for example, as interior trim or finish in automobile bodies, by transferring to the sheets an ornamental pattern simulating the appearance of a wood grain.

One of the objects of the invention is to provide a machine of the foregoing character which, by virtue of its novel construction and arrangement of parts, is capable of producing a superior grade of grained work pieces at a higher rate of speed than has been possible with previous machines of this general nature.

Another object of the invention is to provide a machine having automatically operated vacuum or suction means for picking up and transferring successive work pieces from a stack or pile to conveyor means which conveys or supplies the work pieces to the graining mechanism of the machine.

Another object is to provide a machine having means arranged in cooperative relation to the conveyor means for accurately positioning or aligning the successive work pieces with relation to the conveyor and graining mechanism.

A further object is to provide a machine having means located within the pressure roll and cooperable with the printing roll for engaging the advance edges of the successive plates or work pieces to ensure their proper positioning or alignment with relation to the printing roll, and particularly with relation to the pattern or image on said roll just prior to the printing or graining operation.

Another object of the invention is to provide a machine having a power operated lift or elevating device for a stack of metal plates or sheets for moving and maintaining each successive plate at the top of the stack in position at a predetermined level or plane to be engaged by the transfer means.

Another object of the invention is to provide electric motor or other control means for operating the elevator or lift platform which is located in the path of movement of the successive work pieces or plates removed from the top of the stack and engaged thereby to intermittently operate the motor to lift the stack of plates a predetermined distance.

Another object of the invention is to provide an improved graining machine in which the upward movement of the lift and the travel of the conveyor means are synchronized to ensure the movement or travel of the work pieces to the

printing mechanism of the machine in properly timed relation to the operation of said printing mechanism.

A further object of the present invention is to provide means located above the stack of work pieces or plates and adapted to be engaged by an edge or edges thereof for flexing or cupping the plate being removed from the top of the stack to ensure the release thereof from the next subjacent and other plates of the stack.

The above and other objects and advantages of the invention will appear from the following description and appended claims when considered in connection with the accompanying drawings forming a part of this specification wherein like reference characters designate corresponding parts in the several views.

In said drawings:

Fig. 1 is a perspective view of the machine embodying the present invention, looking toward the left front corner thereof.

Fig. 2 is a perspective view of the machine, looking toward the right rear corner thereof.

Fig. 3 is a longitudinal vertical section of the machine taken substantially along the line 3—3 of Fig. 1, looking toward the right in the direction of the arrows.

Fig. 4 is a top plan view of the machine of the preceding figures.

Fig. 5 is an enlarged fragmentary transverse vertical section taken substantially along the line 5—5 of Fig. 3, looking in the direction of the arrows.

Fig. 6 is an enlarged fragmentary transverse vertical section taken substantially along the line 6—6 of Fig. 3, looking in the direction of the arrows.

Fig. 7 is an enlarged longitudinal sectional view, partly in elevation, showing the plate lifting and shifting or transferring mechanism in position above the stack of plates.

Fig. 8 is a view similar to Fig. 7, showing the plate lifting and shifting mechanism in plate engaging position.

Fig. 9 is an enlarged detail sectional view, partly in elevation, taken substantially along the staggered line 9—9 of Fig. 6, looking toward the right in the direction of the arrows.

Fig. 10 is an enlarged horizontal section taken substantially along the line 10—10 of Fig. 3, looking in the direction of the arrows.

Fig. 11 is an enlarged detail sectional view taken substantially along the line 11—11 of Fig. 10, looking in the direction of the arrows.

Fig. 12 is an enlarged fragmentary elevational

view, partly in section, taken substantially along the line 12-12 of Fig. 5, looking in the direction of the arrows.

Fig. 13 is an enlarged fragmentary section taken through the pressure roll of the graining mechanism of the machine.

Fig. 14 is an enlarged elevational view, parts being broken away, taken substantially along the line 14-14 of Fig. 13, looking in the direction of the arrows; and

Fig. 15 is a perspective view of a work piece, such as a grained metal plate or sheet produced by the machine.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring now to the drawings, the base or supporting structure of the present machine, as shown, comprises a pair of spaced longitudinal channels 16 which rest upon the floor. Mounted upon each of these channels and resting edgewise thereon is a metal bar 17. A platform 18 is mounted upon the bars and, as shown, is fastened thereto in any suitable manner, as by means of bolts. The platform 18 serves as a support for the plate or sheet elevator or lift and the mechanism for operating it, as will be explained below. Beyond the inner ends of each of the bars 17 there is mounted upon the channel 16 a cast metal base member 19 of stepped formation. These members are identical at each side of the machine. Mounted upon the platform 18 and each of the members 17 is an upright support 20, one at each side of the supporting frame structure. Each of the supports 20 is provided with an enlarged base portion 21 to provide a greater supporting surface for the members 20.

There is shown as a whole at 22 the side frame members or upright standards for the printing mechanism of the machine, one being provided at each side of the machine. Each standard or unit 22 is provided with a rear leg 23 and a front leg 24, the leg 23 resting solidly upon the lower stepped portion of the metal base 19 and the leg 24 resting in like manner upon the higher stepped portion of the base. The legs 23 and 24, as shown, are reinforced and braced by substantially horizontally disposed brace members 25. Each of the front legs 24 is connected with an upright member 20 by a horizontal brace member 26.

A pair of transversely spaced substantially horizontal side frame members 27 is provided for the purpose of supporting the horizontally disposed conveyor mechanism of the machine, to be described hereinafter. Each frame member 27 is bolted at 27a to one of the standards 22, the front end of the member being bolted at 27b to one of the upright supports 20. At each side of the machine, a horizontally disposed frame member and guide 28 is provided which is connected at its rear end to the upright 20 by means of the bolt 27b and has its forward portion toward the entrance or front end of the machine

supported by a diagonally disposed or upright brace member 29. This brace member 29 has its opposite ends secured to the frame member 28 and to the upright 20, respectively. The uprights 20 are connected together and braced by means of a horizontal transverse brace bar 30 which may be bolted at opposite ends to the uprights 20. A rod or shaft 31 also extends transversely of the machine between the uprights 20 and is secured thereto. A bar 32, similar to the bar 30, is provided for connecting the uprights 20 together adjacent their upper ends. In this connection, reference should be had to Figs. 1, 3 and 5.

The adjustable frame or guide for the work pieces

An upright rectangular frame structure which, as shown, comprises four spaced upright angle bars is provided at the front end of the machine and serves as a combined guide and aligning means for a stack or pile of metal plates or sheets which are to be elevated into an accessible position by the lift platform of the elevating mechanism. As best seen in Figs. 1, 3, 5 and 10, a pair of rear or inner transversely spaced upright angles 33 and 34 is provided which are adapted to cooperate with a pair of similar transversely spaced front upright angles 35 and 36. The rear angle bars 33 and 34 are supported at their upper ends by the horizontal bar 32 by means of brackets (not shown) carried by the rear faces of the angles. Referring especially to Figs. 5 and 10, it will be seen that the rear angle bars 33 and 34 are supported intermediate their upper and lower ends by brackets 37 which, as shown, are carried by the rod 31. The angle bar 33 is capable of being adjusted transversely of the machine relative to the bar 34.

The front angles 35 and 36 are supported adjacent their upper ends by means of a horizontally disposed frame structure which, as shown, comprises metal bars 39 and 40 extending transversely of the machine connected together in spaced relation at opposite ends by means of composite blocks 41, 42, see particularly Fig. 1. Each of the blocks, as shown, has a superimposed cap piece or portion 41a, 42a, respectively, of angle formation provided with a pair of adjusting screws 43. The groove or guideway between the base or block and the horizontal portion of the cap piece is adapted to receive the forward portion of one of the side frame members or guides 28. Thus the frame structure 39, 40, etc., as a unit, may be adjusted horizontally along the supports and guides 28 to change or adjust the position of the front angle bars 35 and 36 relative to the corresponding rear angle bars 33 and 34.

The connecting means between the angle bar 35 and the bar 39 is, as shown, a block 44 which is attached to the angle and has a pair of slots 44a forming therein (see particularly Fig. 4. 65 Adjusting screws 45 and 46 are provided which extend through the slots and into the frame member 39. Therefore, the top portion of the angle bar 35, as well as being capable of adjustment longitudinally of the machine toward and away from the rear angle 33, is also capable of being adjusted transversely of the machine relative to the frame member 39 toward and away from the opposite front angle 36. A block 47, Figs. 1 and 4, is secured to the front face of the angle 36 adjacent the top thereof and bolted or

otherwise secured to the frame member 39. The block 47 as shown, is fixed to the member 39.

The lower ends of the upright angles 33 and 35 are connected together by means of a longitudinal bar or member 48 slotted at its forward end at 49 to receive the shank of a two-part bolt and nut fastening and adjusting device 50 which has, as shown, a releasable round head or gripping portion which may be unscrewed to loosen the connection. The bolt is held fast in a hole or opening formed in the angle 35 so that it cannot rotate with the head portion of the fastening device.

The lower ends of the angle bars 34 and 36 are adjustably connected together in a manner similar to the angle bars 33 and 35, by means of a horizontally disposed angle bar or member 51. The outer or front end of this horizontal bar is slotted to cooperate with a fastening device 52 which is similar to the device 50. A bracket, such as the L-shaped bracket 53 of Fig. 5, is provided to brace the angle member 51 which connects the upright angles 34 and 36 and to likewise steady or brace said angles. The outer end of the bracket 53, as shown, is attached by rivets to the horizontal leg or portion of the angle member 51. The inner end of the bracket or brace member is bolted at 53a to the adjacent wall 55 of a housing or enclosure forming a part of the plate elevating or lift mechanism to be described hereinafter.

The purpose of the spaced upright angle bars 33, 34, 35 and 36 is to provide, as stated above, a skeleton framework for engaging and guiding the corner edges of the metal sheets or plates constituting the stack or pile P resting upon the elevator or lift platform E, see Figs. 1 and 5. By providing for the relative adjustment in different directions of certain of the corner upright angle bars, stacks of plates or sheets of different sizes can be accommodated. Moreover, such adjustment will also take care of any variations or tolerances in the size of the plates or sheets in a single stack or pile.

From the above it will be understood that the inner left angle bar 33 may be adjusted bodily toward or away from the corresponding back angle bar 34 in a direction transverse of the machine. The front or outer angle bars 35 and 36 may be adjusted bodily toward and away from their corresponding back angle bars 33 and 34, respectively. The left front angle bar 35 is also permitted a range of adjustment toward or away from the corresponding front angle 36 in a direction transverse of the machine. With adjustments such as described it will be understood that the skeleton framework will readily accommodate itself to stacks or piles of plates or sheets of varying size and dimensions.

As best seen in Figs. 1, 2 and 10, a reinforcing and strengthening gusset plate 54 is preferably bolted to the rear edge of the platform 18 with its vertical edge abutting and, if desired, attached to the adjacent wall of the housing H to provide a brace for one side of said housing.

The stack elevator or lift and operating mechanism therefor

The elevator or lift platform and operating mechanism therefor will now be described. The housing, shown as a whole at H, see particularly Figs. 3, 5 and 10, comprises, as seen, a pair of side vertical walls 55, 55 and a top wall or cover 56, the latter having a hole or opening 57 formed therein. Mounted upon the cover 56 is a block-like gear box 58 having intercommunicating

pockets or recesses 59 and 60 formed therein. An internally threaded worm gear or wheel 61 is disposed within the recess 59 and a cooperating worm 62 is located within the pocket or recess 60. The worm 62 is fixed to a horizontal shaft 64 which has a bearing in spaced sleeves or bushings 63, Figs. 5 and 10. The gear box 58 is provided with separate cover plates 65 and 66. A short sleeve or hub 63a extends forwardly beyond the side wall of the box and surrounds the reduced portion 64a of the shaft 64. The outer end of the hub is enlarged at 63b and provided with spaced teeth or lugs to form one part of a toothed clutch mechanism. The short sleeve 63a has fixed to it, as by spot welding, a gear or sprocket 67, Fig. 10.

The lift platform or elevator proper is shown as a whole at E. As shown, this platform comprises a central elevated or raised section 68 and two side lower sections 69, 69, connected together by upright pieces 68a. Mounted on each of the sections 69, preferably at the outer edge of each section, is a wood block 70. The top faces of the blocks are, as shown, in substantially the same plane as the top face or surface of the central section 68. At front and back the platform sections 68, 69, 69 have attached thereto depending members or skirts 71, see particularly Fig. 5. Attached to the underface of the section 68 is a metal plate or block 72 which is preferably held in place by cap screws or bolts 73 having countersunk heads. The platform E is supported by means of an externally threaded feed screw 74 which extends through an opening in cap plate 65 and is threaded through the internally threaded socket of the worm gear 61. Below the worm gear the feed screw projects through the opening 57 and into the housing or framework H. The upper end of the screw 74 has a plain reduced shank portion or extension which is rotatably mounted in a socket formed in the attaching or bearing plate 72. Thus, when the worm wheel 61 is rotated in one direction by the worm 62, the screw will be projected upwardly from the gear box 58 to elevate the platform E. When the worm gear is rotated in the opposite direction the screw 74 will be retracted to lower said platform. As explained hereinafter, the platform E is moved upwardly by power operated means actuated, for example, by an electric motor, and is lowered by manual means.

Referring particularly to Fig. 10, the worm gear shaft portion 64a extends outwardly beyond the fixed clutch element 63b and carries at its outer end a second fixed clutch element 75. A sprocket 76 is spot welded to this clutch element adjacent a locking ring or stop 77. A third shiftable clutch element 78 is mounted on the shaft portion 64a between the non-slidable elements 63b and 75 and is slidably keyed to the shaft at 79. A clutch fork 80 engages the body portion of the slide clutch element 78. A depending pin 81 carried by the fork fits within a socket 83 formed in a bar or lever 82 for actuating the fork, see Fig. 11. The lever 82 is provided with a forwardly projecting operating handle 84. The clutch lever, as shown, is supported by a pair of attached blocks 85 and 86, the block 86 being bolted at 87 to the side wall 55 of the elevator housing H. The clutch lever 82 is mounted for oscillatory movement through the medium of the handle 84 by means of a pivot pin 88 which extends through the lever and is socketed in the block 85. Thus, by moving the handle 84 in and out the intermediate slideable clutch element 78

may be engaged with either one or the other of the fixed clutch elements 75 and 63b. As will be seen hereinafter, the sprocket 67 is interconnected with suitable electric motor driven gearing for elevating the platform, whereas the sprocket 76 is chain connected with suitable hand operated gearing for lowering the platform.

The power operated means for raising the platform E comprises, as shown, an electric motor 89 for driving suitable reduction gearing contained in a gear case 90, both being mounted as a unit upon the platform 18. The gearing drives a shaft 91, see Fig. 3, which carries a gear or sprocket 92 held in place upon the shaft by a locking ring or collar 92a. A sprocket chain 93 provides the driving connection between the sprocket 92 and the sprocket 67 on the worm shaft sleeve 63a. Thus, when the motor 89 is driven and the clutch control handle 84 is actuated to interengage the clutch parts 78 and 63b, the worm 62 and the worm gear 61 are rotated to project the elevator screw 74 and raise the platform E. The speed of movement of the platform in an upward direction is relatively slow due to the reduction gearing in the gear box 90.

The hand operated mechanism for lowering the platform E comprises a horizontal shaft 94 journaled in a bearing 95 on a bracket 95a supported by the gear case 90. The shaft's inner end is journaled in a bearing 96 which, as shown, is mounted upon a wall 55 of the elevator housing, see Fig. 3. The shaft 94 has a crank disk 97 fixed to its outer end. A crank arm 98 is attached to the disk and carries an operating handle 99. The shaft 94 also has fixed to it adjacent the bearing 95, a gear or sprocket 100 of relatively large diameter. A sprocket chain 101 provides a driving connection between the sprocket 100 and the sprocket 76. By shifting the intermediate clutch element 78 to the right of Figs. 3 or 10 and into engagement with the clutch element 75 and then rotating the shaft 94 by its crank connection, the elevator screw 74 will be retracted or lowered to lower the platform E. This lowering operation occurs at a relatively high rate of speed due to the ratio of the gears or sprockets 100 and 76 and the eccentric mounting of the crank arm 98.

When the machine is in operation and as will be fully described hereinafter, the upward movement or travel of the lift platform E is intermittent and at a low rate of speed timed in accordance with the speed of operation of the mechanism for transferring the plates from the platform to conveyor mechanism which carries them to the printing mechanism. In other words, the upward travel of the elevator with its stack of metal plates is timed so as to position the top-most plate of the stack at the proper level or plane and at the time that the transfer mechanism is in a position to engage and lift it off the stack.

As the top plate is lifted off the stack P by the transfer mechanism about to be described, its front edge engages a movable contact member 103 of a switch mechanism housed within the switch box 102. The latter is supported above the cross frame member 39 by a bracket or support 104. So long as the plate is in engagement with the contact 103 the electric motor 89 will be energized and the elevator actuating mechanism operated. This operation continues just long enough to move the stack upward the proper distance to place the new top plate of the stack, i. e. the next subjacent plate therein, in the po-

sition just vacated by the removed top plate. When the top plate which is being removed releases the contact 103, the motor is deenergized and the elevator stopped. The switch 102 and the motor 89 are electrically connected by a conduit or cable 105.

When a stack of plates has been exhausted it is desirable to reload the elevator or lift platform as quickly as possible so as to minimize the idle period of the machine. For this reason the above described manually operated platform lowering mechanism has been provided, this mechanism including high speed gearing permitting the easy and rapid lowering of the platform for reloading purposes.

The sheet transfer mechanism

The transfer mechanism for lifting the successive plates from the top of the stack and placing them onto conveyors which carry them to the printing or graining mechanism, will now be described. The transfer mechanism in accordance with the present embodiment is best shown in Figs. 1, 3, 4, 7, 8 and 12 and, as herein illustrated, includes vacuum or suction operated means, such as cups, mounted upon a carriage or frame work capable of being shifted from a position above the stack of plates P to a position overlying the entrance end of endless conveyor mechanism for carrying the sheets to the printing or graining unit or mechanism of the machine.

The carriage or movable frame portion of the plate transfer mechanism is supported at its front end for raising and lowering as well as longitudinal reciprocating movements by slide bars or members 106 which are adapted for vertical up and down movements within guide blocks 107. As clearly seen in Figs. 1 and 12, each of the blocks 107 is supported in upright position by the upper offset end portion 20a of the uprights or standards 20 and by means of a bolt 108 which secures the block to the standard. Each slide member 106 is provided with an inwardly projecting stud or pin 109 which carries a sleeve and washer or disk 110 secured to the stud and to the slide by a nut 111. As best seen in Fig. 5 the stud or member 109 at the right side of the machine, looking from the front, is longer than the corresponding member at the left side thereof so as to allow a space or clearance for the drive gearing located at the right side of the machine.

The carriage or framework of the transfer mechanism comprises two similarly formed longitudinal bars or members 112 having enlarged portions at their forward ends toward the front of the machine which are provided with slots 113. The slots 113 extend rearwardly of the bars or members 112 in substantially horizontal planes for approximately one-half the length of said bars, the inner or rear ends of the slots being curved upwardly and rearwardly at 114. The inner or rear terminal ends of the bars 112 are connected together in spaced relation by a transverse rod 115 upon which the bars are pivotally mounted. The sleeved pins or members 109 project through the slots 113 and thus the carriage members 112 may slide in a longitudinal direction relative to the members 109. The inner end of the frame or carriage is supported at opposite sides by upright bars or members 116 whose upper ends are pivotally mounted upon the transverse rod 115. The lower ends of the bars are pivotally supported upon a transverse

rod or shaft 156 and intermediate their ends they are attached to a power drive mechanism for rocking or oscillating them and likewise reciprocating the carriage in a longitudinal direction. This oscillating mechanism is located at each side of the machine and carried by the side frame members 22. As shown, a crank or bar 117 is oscillated by means of a crank disk 118, there being provided an eccentrically mounted pin carried by the disk which engages in a slot formed in the member 117. The lower end of the oscillatable member 117 and the bar 116 are connected by an adjustable link or rod 119 and a laterally projecting stud or the like 120, the latter being attached directly to the member 116. It will be understood that similar connections and oscillating means may be provided at each side of the machine so that both of the upper bars are operated simultaneously.

The carriage or frame members 112 support a transverse horizontal shelf or member 122 which provides means for supporting plate engaging members which, as shown, comprise a pair of depending vacuum or suction cup devices 123. As seen in Fig. 1, the carriage and suction cup devices are in their rearmost position and the cups are shown as supporting one of the metal plates or sheets F in position above and prior to its release onto the endless belts of the conveyor mechanism to be described.

In Figs. 7 and 8 the carriage comprising the longitudinal members 112 is shown in two of its forward positions with the vacuum or suction cups being positioned above the stack of metal plates or sheets. In Fig. 7 the cups are in elevated position and in Fig. 8 are in lowered position with the cups in engagement with the top plate of the stack ready for the removal operation. When the cups are lowered from the position of Fig. 7 to that of Fig. 8 vacuum or suction is applied so that the cups grip the top plate adjacent its inner edge. As the mechanism functions to shift the slotted bars 112 upwardly or toward the rear of the machine, the upwardly curved portion 114 of the slot will ride over the member 109 and lift or elevate the cups. As the top plate is elevated by the cups, the inner side edges of the plate contact cam members or blocks 33a and 34a, see particularly Fig. 5, so as to buckle or upwardly bow the plate or sheet until it is free of the members 33a and 34a to insure its release from the next subjacent plate of the stack. Further movement of the slotted members 112 toward the rear of the machine will cause the horizontal portions of the slots to travel over the studs 109 until the carriage and its supported plate reach substantially the position in which these parts are shown in Fig. 3. At this point, the vacuum is broken by an automatically actuated release valve and the plate falls into position upon the endless conveyor mechanism. By reason of providing the vertically reciprocable slide members 106, the vacuum cups are permitted to be raised and lowered relative to the stack of plates.

The mechanism for controlling the vacuum or suction in the cups 123 is shown in Fig. 12 which indicates the position of the parts as a plate is released by the vacuum cups and falls onto the endless conveyors. The lower end of each of the slides 106 carries an outwardly projecting stud or bolt 124 to the outer end of which is attached a vertically extending rod 125. The rod projects upwardly through a hole formed in the flange 126a of an angle bracket 126 which is attached,

as shown, to the outer face of the standard 20. A coil spring 127 surrounds the rod and finds a seat at its lower end upon the horizontal flange 126a. A knurled adjusting nut 128 is applied to the upper screw-threaded end of the rod 125 and engages the upper end of the spring so as to vary the compression of said spring. A lock nut 129 serves to maintain the knurled nut in position. Thus far, the structure, including the parts 124 to 129 inclusive, is substantially the same at both sides of the machine. At the right hand side of the machine, referring particularly to Fig. 12, additional elements are provided for actuating a vacuum relief valve. As shown, each stud or bolt 124 carries a dog member 130 which is pivotally mounted at 131 upon the outer face of standard 20 and has a nose or projection 130a. A rotatable shaft or rod 132 extends transversely of the machine from side to side and carries adjacent each end thereof, outside the standards 20, a cam member 133 having a peripheral projection or nose 133a.

The shaft 132 is driven by a chain 132a located at the left hand side of the machine through sprockets 132b and 132c, the latter sprocket being mounted upon a similar transverse shaft 132d. The chain 132a is provided with a slack take-up device shown generally at 132e. Thus the cam 133 at the right side of the machine is driven or rotated in a clockwise direction, as indicated in Fig. 12, whereas the similar cam at the left side is simultaneously driven in a counterclockwise direction, so that the nose 133a of each cam will intermittently move its associated dog member 130 in a downward direction against the action of the spring 127. At the right hand side of the machine there is located the vacuum release valve shown as a whole at 134, Fig. 12. This valve is in communication with the vacuum pump 135, see Figs. 3 and 12, by means of a conduit or pipe 136. The vacuum valve is also in communication with the vacuum cup devices 123 by means of conduits or flexible tubing 137, see Figs. 1, 3 and 4. The valve chamber 134 is provided with a disk valve 138 carried by a valve lever 139 which is pivotally mounted at 140 upon the casing. The lever extends beyond the valve disk in the direction of the rear end of the machine and has an inclined underside or surface 141 at its free end. A substantially L-shaped dog member 142 is pivotally mounted at 143 upon the standard 20 adjacent the nose or end portion 141 of the valve lever and is connected by means of an adjustable screw threaded rod or link 144 to a short operating lever 145 which is rotatably mounted upon the transverse shaft 132. An actuating rod 146 has one end pivotally connected at 147 to the lever 145 to rock it back and forth and extends longitudinally toward the rear of the machine, its rear end being mounted upon an eccentric or crank disk or block, see Fig. 4. As the lever 145 is oscillated by the crank connecting rod 146, the nose of the dog 142, through the adjustable connection 144, periodically engages and lifts the valve lever 139 to raise the valve 138 from its seat to relieve or break the vacuum in the vacuum cup lines and, of course, in the vacuum cups. As the cam 133 is rotated in a clockwise direction as indicated by the arrow in Fig. 12, the nose 133a of this cam will periodically engage the nose 130a of the dog member 130. During such engagement, see the broken line position of the parts in Fig. 12, the dog 130 is moved in a counterclockwise direction about its pivot 131 to draw the rod 125

down against the action of the spring 127 and at the same time to move the slide 106 downwardly. The operation is so timed or synchronized that when the nose 133a of the cam is in engagement with the nose 130a of the dog member 130, the dog 142 is out of engagement with the valve lever 139 and thus the valve remains closed while the vacuum line and cups are subjected to vacuum or suction from the pump 135. As seen in Fig. 3, the vacuum pump is driven by a motor 148 through a belt or chain 149. A vacuum device or chamber 150 is interposed in the line between the vacuum pump 135 and the vacuum valve chamber or casing 134. When the parts are in the full line positions of Fig. 12, that is with the member 130 out of engagement with the nose 133a of the cam 133, the vacuum line and the vacuum cups are relieved of vacuum due to the unseated or elevated position of the vacuum valve 138. When, however, the parts 133 and 130 assume their broken line positions of Fig. 12 the vacuum lines and the cups are subjected to vacuum, in which position the dog 142 has been moved downwardly and is out of engagement with the valve lever 139, with the valve 138 seated or closed.

Certain of the drive mechanism for the machine is located in the space between the right hand frame member or standard 20 and the adjacent vertical angle bar 34, see Fig. 5. As shown, a transverse shaft 151 extends through the machine and carries adjacent its right end a pinion gear 152. Mounted on the shaft 151 and located inwardly or toward the left from the gear is a sprocket 153 over which a sprocket chain 154 runs and is connected to a sprocket 155 mounted upon a transverse shaft 156 located above the base member 19, see Fig. 3. The shaft 156 also carries a smaller sprocket 156a which is connected by a sprocket chain 158 to a gear or sprocket 156b mounted on the shaft 132d adjacent the top of the machine. The gear 156b and the shaft 132d are driven by means of a small pinion 156c with which the gear 156b meshes. The pinion 156c is driven by a gear train forming a part of the printing or graining mechanism of the machine and including a shaft 156d carrying a sprocket 156e connected by chain 156f to a pulley 199. As best seen in Fig. 3, from shaft 156 the drive is through the large sprocket 155, chain 154 and sprocket 153 to the shaft 151.

The transfer mechanism is designed to engage and remove the top plate of the stack and to transfer it from its elevated position above the stack to the conveyor without allowing any portion of the plate being transferred to come in contact with the next subjacent plate of the stack. By thus lifting the top plate entirely above the stack before carrying in a forward direction toward the conveyor mechanism, any possibility of scratching or marring one plate by another plate is prevented. A very strong vacuum is present in the vacuum devices 123 and it is practically impossible to remove a plate from the vacuum devices without first breaking the vacuum.

Referring particularly to Figs. 1, 4 and 5, there is shown, as a whole at 250, means for subjecting the successive top plates of the stack P to a blast or blasts of air just prior to their transference to the conveyor which feeds them to the graining mechanism of the machine. As shown, the member 250 is in the form of a drilled and orificed block attached to the cross bar 32 and is provided with two outlet ducts or orifices 251, 251 which connect with passages 252 of V-formation lead-

ing from an air pipe or conduit 253 and an elbow, coupling or fitting 254. The discharge ducts or orifices 251, as shown, discharge blasts of air toward the plate being removed in the plane or substantially the same plane as that of the lugs or members 33a, 34a, which engage and flex the successive top plates being removed. The air blast or blasts may be useful to assist in breaking any suction or vacuum which exists between the topmost plate of the stack and the next subjacent plate thereof, and/or to remove any dust or other loose foreign matter which it might be desirable to remove from the plate being transferred from the stack to the conveyor prior to the graining operation. Compressed air from any convenient source is supplied to the pipe or conduit 253 by attaching, for example, an air hose to the valve casing 255, see Fig. 1.

The conveyor mechanism

The conveyor mechanism which receives the metal plates or sheets from the transfer mechanism comprises, as shown, a plurality of transverse rolls 160, five such being shown in the present embodiment. These rolls are rotatably journaled at opposite ends in the longitudinal side frame members 27, see Fig. 4. A plurality of transversely spaced endless belts or bands 161 travel over the rolls 160 and are adapted to be driven in any suitable manner as, for example, by providing a driving connection for the roll nearest to the front end of the machine. A pair of pressure rolls 162 is provided to cooperate with the belts and with two of the rolls 160, see Figs. 3 and 4, these rolls being mounted upon levers 163 which are urged downwardly by tension springs 164. The levers are pivotally mounted in the side frame members 27. Thus the pressure rolls cooperating with the rolls over which the belts travel serve to maintain the work pieces flatwise during their travel with the conveyor belts.

For the purpose of maintaining the metal plates P in alignment and to insure their travel in a straight line path on the conveyor belts, there is provided at the right hand side of the machine a longitudinally extending guide member 165. The front end of the member 165 is preferably attached to the vertical angle 34 and it is supported at other points from the frame member 27 by means of spaced studs or bolts 166, see Fig. 4. At the opposite side of the machine, namely the left side thereof looking from the front end of the machine in Fig. 1, a similar guide 167 is provided. This guide is supported from the side frame member 27 by means of horizontal rods 168 which extend through holes in the frame 27. The guide 167 is also connected at its front end to the adjustable upright angle 33. The guide 167 is adjustable transversely of the machine toward and away from the guide 165 and is capable of being held in any adjusted position by means of screws or bolts 169. Thus it will be seen that if it is desirable to adjust the stack guides or frame members 33 and 35 transversely of the machine the guide 167 may also be adjusted so as to compensate for any change in the position of the members 33 and 35. Therefore, it will be understood that the relative adjustment of the guides 165 and 167 permits their use with plates or sheets of varying widths in a direction transverse of the machine.

Plate stops and aligning devices

It is desirable to maintain the metal plates in predetermined positions during their travel through the machine and particularly to have them in proper alignment prior to their coming in contact with the graining or printing cylinder or device. For this purpose there is provided positive means which is cam operated in predetermined timed relation with the movement of the conveyor mechanism and the operation of the graining mechanism to momentarily check the movement of each sheet and insure its proper alignment prior to its engagement with the graining cylinder. As shown, there are provided two or more pivotally mounted oscillatable hook-like members or stops shown as a whole at 170 which are located between the belts 161 and when in operative position have their free end portions 171 projecting upwardly slightly above the top courses of the belts. Each of the stop devices is, as shown, mounted upon a common transverse shaft 172 and has a depending portion or leg 173 carrying a roller 174. The roller is adapted to be held in contact with a cam 175 by means of a tension spring 176. The cam is mounted upon a transverse rotatable shaft 177. The shaft carries a series of cams one for cooperation with each of the hook members or stops 170. As the cams are rotated the hooked ends 171 of the stop devices are either projected upwardly or retracted in timed relation to engage or release the forward edge of one of the plates. In Figs. 8 and 9 the hooks are shown in operative relation engaging the adjacent edge of a work piece or plate P. In Fig. 7, however, the hook member 170 has been retracted to its lower position permitting the belts 161 to carry the released plate P toward the graining mechanism. A plurality of pressure devices, three being shown and indicated generally at 178, are mounted upon a transverse supporting bar or cross frame member 179. Each of these pressure devices carries at its lower end a contact roller 180 which, as shown, is adapted to engage the top face of the plates as they are moved by the conveyor belts. The pressure devices in cooperation with the hook members or stops 170 maintain the plates in the proper position for passage to the graining cylinders or rolls. The pressure devices are independently adjustable transversely of the machine along the supporting member 179. Thus they can be moved to any desired position. As best seen in Fig. 6 the transverse bar 179 is supported above the endless conveyor mechanism by bars or brackets 179a which are mounted upon the longitudinal frame members 27. As seen also in this figure the pressure devices 178 are vertically adjustable relative to the belts 161 by means of adjusting screws 178a.

The graining mechanism

The graining mechanism herein shown is generally of conventional form with the exception of the pressure roll per se. There is provided the conventional series of small and large ink distributing rolls shown as a whole at 181 which receive ink from the trough 182 and apply it to the surface of the transfer roll 183 which in turn transfers the ink to the image containing band or cover for the printing roll 184.

As best seen in Figs. 3, 13 and 14, the pressure roll of the present invention is shown as a whole at 185. This roll, as seen, has a portion of its

periphery removed at 186, the adjacent peripheral portions of the roll being flanged inwardly at 187. The end walls of the drum or roll 185 provide bearings or supports for the opposite ends of a transverse shaft 188. Mounted upon this shaft and oscillatable thereupon is a plate positioning and aligning bar or stop member 189 which is attached to hub-like members 190 located adjacent opposite ends of the shaft 188 and oscillatable upon the shaft. These hub-like members or brackets are provided with stop screws 191 which are adapted to engage the adjacent flange 187 of the roll when the members 190 and 189 are rocked about the shaft in a counterclockwise direction. Each hub portion 190 is also provided with an inwardly projecting plate or member 192 to the free end of which a coil spring 193 is attached. The opposite end of the coil spring is attached at 194 to the drum. These tension springs 193 tend to maintain the bar or member 189 normally in its projected position as seen in Fig. 13. It remains in this position until the pressure roll 185 has rotated sufficiently in a counterclockwise direction to cause the bar 189 to contact the periphery of the adjacent printing roll 184 which contact rotates said bar in a clockwise direction about the shaft 188 so that it assumes its retracted position as shown in Fig. 3 as long as it is in engagement with the periphery of the printing roll. As soon as the bar is free from contact with the printing roll, the spring or springs 193 again project it through the opening 186. After a plate P has been released by the stop members 170, Figs. 7, 8 and 9, and is moved by the conveyor belts toward the bite of the printing roll 184 and pressure roll 185, the lead edge of the plate comes in contact with the gauge bar or member 189, thus positioning said lead edge properly to be engaged by the image or ornamental graining design carried by the printing roll. In other words, the lead edge of the plate and the lead edge of the design or pattern on the printing roll meet and register at the proper time so that the entire surface of the plate will have the graining transferred from the printing roll to it, thus eliminating any possibility of blank or unprinted portions on the surface. It will be understood that the bar acts as a stop only momentarily and further rotation in a clockwise direction of the pressure roll will depress the gauge bar and permit the plate to be carried through the rolls to effect the graining or printing thereof. After the plate issues from the bite of the rolls 184 and 185 it is moved onto a conventional endless conveyor 195 by which it is carried onto a second or auxiliary endless conveyor 196. To prevent any possibility of the plate tilting upwardly and jamming or having its movement retarded, or its surface graining marred, there is provided a guide roll 197 located above the conveyor 195 and in the space below the contacting surfaces of the rolls 183 and 184.

Conventional drive mechanism is provided for the conveyor belts and for the transfer, printing and pressure rolls, as well as for the conveyors 195 and 196. The multi-stage pulley mechanism shown generally at 198 and 199 and interconnected by a driving belt or chain 200 is provided for varying the speed of operation of certain parts of the machine. An electric motor 201 serves as a source of power for driving the pulley mechanism, the motor being connected in driving relation with the lower pulley 198 by a drive belt or chain 202. The particular driving means

and connections for driving the rolls of the graining mechanism may be of any conventional type suitable for the purpose. It will be understood, however, that all of the drive mechanism for the different units of the present machine operate in timed relation to one another and are synchronized so that there is a substantially continuous movement of the work pieces through the machine and to, through and away from the graining mechanism thereof.

In Fig. 15 there is shown a perspective view of a finished work piece such as a metal plate or sheet P with one design or graining applied to a surface thereof. This finished work piece serves to illustrate the point referred to above which is accomplished by the gauge member or stop 189 and that is to properly align and position each of the work pieces P with relation to the printing roll so that the entire top face or surface of the work piece is covered by the design carried on the printing roll.

I claim:

1. In a machine for applying graining to metal surfaces such as plates, sheets, or the like, including graining mechanism adapted to contact opposite faces of successive plates delivered thereto to apply graining to one of the faces, in which the machine also includes means for supporting and elevating a plurality of stacked plates into position to be transferred to the graining mechanism; feeding apparatus for the plates comprising a conveyor for supplying the plates in successive order to said graining mechanism, vacuum means movable into engagement with the successive plates for transferring them onto said conveyor, stop members associated with the conveyor and movable into the path of travel of the plates to momentarily arrest their movement toward the graining mechanism, and means adapted to contact the plates for aligning the same prior to their engagement with the graining mechanism of the machine.

2. In a machine for applying graining to metal surfaces such as plates, sheets, or the like, including graining mechanism adapted to contact opposite faces of successive plates delivered thereto to apply graining to one of the faces, in which the machine also includes means for supporting and elevating a plurality of stacked plates into position to be transferred to the graining mechanism; feeding apparatus for the plates comprising a conveyor for supplying the plates in successive order to said graining mechanism, vacuum means movable into engagement with the successive plates for transferring them onto said conveyor, stop members associated with the conveyor and movable into the path of travel of the plates to momentarily arrest their movement toward the graining mechanism, and a movable stop member adapted to contact the lead edges of the plates for aligning the same immediately prior to their passage through the graining mechanism of the machine.

3. In a machine for applying graining to metal surfaces such as plates, sheets, or the like, including graining mechanism adapted to contact opposite faces of successive plates delivered thereto to apply graining to one of the faces, in which said mechanism comprises transfer, printing and pressure rolls, and in which the machine also includes means located at the front end thereof for supporting and elevating a plurality of stacked plates into position to be transferred to the graining mechanism; feeding

apparatus for the plates comprising a conveyor for supplying the plates in successive order to said graining mechanism, and vacuum means movable into engagement with the successive plates at the top of the stack for transferring them onto said conveyor, said machine including separate conveyor means located at its rear end for removing the grained plates.

4. In a machine for applying graining to metal surfaces such as plates, sheets, or the like, including graining mechanism adapted to contact opposite faces of successive plates delivered thereto to apply graining to one of the faces, in which said mechanism comprises transfer, printing and pressure rolls, the pressure roll having a longitudinal opening in its periphery and also including an oscillatable stop member extending between the ends of the pressure roll and adapted to be projected through said roll opening into position to be engaged by the successive plates to align the same immediately prior to their engagement by the printing, pressure and transfer rolls, said machine also including means for supporting and elevating a plurality of stacked plates into position to be transferred to the graining mechanism; feeding apparatus for the plates comprising a conveyor for supplying the plates in successive order to said graining mechanism, vacuum means movable into engagement with the successive plates for transferring them onto said conveyor, said machine including an endless conveyor for supporting and moving the plates beyond said rolls, and means associated with said conveyor to prevent tilting of the plates during their movement.

5. In a machine for applying graining to metal surfaces such as plates, sheets, or the like, including graining mechanism adapted to contact opposite faces of successive sheets delivered thereto to apply graining to one of the faces, in which the machine also includes lift mechanism for elevating a plurality of stacked plates into position to be transferred to the graining mechanism, power means for elevating the lift and plate stack and means engageable by the plates during their transfer from the stack to a conveyor for periodically operating the power mechanism to elevate the lift to position and maintain the succeeding top plates of the stack at a predetermined level; feeding apparatus for the plates comprising a conveyor for feeding the plates in successive order to said graining mechanism, automatically controlled vacuum means movable into engagement with the successive plates at the top of the stack for transferring the plates successively onto said conveyor, and valve means automatically operable at predetermined times to break the vacuum and release a plate onto said conveyor.

6. In a machine for applying graining to metal surfaces such as plates, sheets, or the like, including graining mechanism adapted to contact opposite faces of successive sheets delivered thereto to apply graining to one of the faces, in which the machine also includes lift mechanism for elevating a plurality of stacked plates into position to be transferred to the graining mechanism, power means for elevating the lift and plate stack and means engageable by the plates during their transfer from the stack to a conveyor for periodically operating the power mechanism to elevate the lift to position the succeeding top plates of the stack at a predetermined level; feeding apparatus for the plates

comprising a conveyor for feeding the plates in successive order to said graining mechanism, automatically controlled vacuum means movable into engagement with the successive plates at the top of the stack for transferring the plates successively onto said conveyor, valve means automatically operable at predetermined times to break the vacuum and release a plate onto said conveyor, and automatically operated means associated with the conveyor and adapted to contact the successive plates for aligning the same prior to their engagement with the graining mechanism.

7. In a machine for applying graining to metal surfaces such as plates, sheets, or the like, including graining mechanism adapted to contact opposite faces of successive sheets delivered thereto to apply graining to one of the faces and including transfer, printing and pressure rolls and a movable stop carried by the pressure roll for engagement with the lead edges of successive plates for aligning the plates with relation to the rolls immediately preceding their engagement by the printing roll, in which the machine also includes lift mechanism for elevating a plurality of stacked plates into position to be transferred to the graining mechanism, power means for elevating the lift and plate stack and means engageable by the plates during their transfer from the stack to a conveyor for periodically operating the power mechanism to elevate the lift and position the top plate of the stack at a predetermined level; feeding apparatus for the plates comprising a conveyor for feeding the plates in successive order to said graining mechanism, automatically controlled vacuum means movable into engagement with the successive plates at the top of the stack for transferring the plates successively onto said conveyor, valve means automatically operable at predetermined times to break the vacuum and release a plate onto said conveyor, and automatically operated means associated with the conveyor and adapted to contact the successive plates for aligning the same prior to their engagement with the graining mechanism.

8. In a machine for applying graining to metal surfaces such as plates, sheets, or the like, including graining mechanism adapted to contact opposite faces of successive plates delivered thereto to apply graining to one of the faces, in which said mechanism comprises transfer, printing and pressure rolls, the pressure roll having a longitudinal opening in its periphery and a movable stop member carried by the pressure roll and adapted to be projected through said roll opening into position to be engaged by the successive plates to align the same immediately prior to their engagement by the printing and pressure rolls, in which the machine also includes means for supporting and elevating a plurality of stacked plates into position to be transferred to the graining mechanism; feeding apparatus for the plates comprising a conveyor for supplying the plates in successive order to said graining mechanism, stop members associated with the conveyor and movable into the path of travel of the plates to align the plates and momentarily arrest their movement toward the graining mechanism, and suction cups movable into engagement with the successive plates at the top of the stack for transferring them onto said conveyor.

9. In a machine for applying graining to metal surfaces such as plates, sheets, or the like, in-

cluding graining mechanism adapted to contact opposite faces of successive plates delivered thereto to apply graining to one of the faces, in which said mechanism comprises transfer, printing and pressure rolls, the pressure roll having a longitudinal opening in its periphery and a member carried by the pressure roll and adapted to be projected through said roll opening into position to be engaged by the successive plates to align the same immediately prior to their engagement by the printing and pressure rolls, and in which the machine also includes means for supporting and elevating a plurality of stacked plates into position to be transferred to the graining mechanism; feeding apparatus for the plates comprising a conveyor for supplying the plates in successive order to said graining mechanism, stop members associated with the conveyor and movable into the path of travel of the plates to align the plates and momentarily arrest their movement toward the graining mechanism, and vacuum means movable into engagement with the successive plates for transferring them onto said conveyor, said machine including endless conveyor means for removing the grained plates from the machine.

10. In a machine for applying graining to metal surfaces such as plates, sheets, or the like, including graining mechanism adapted to contact opposite faces of successive plates delivered thereto to apply graining to one of the faces, in which said mechanism comprises transfer, printing and pressure rolls, the pressure roll having a longitudinal opening in its periphery and an oscillatable stop member extending between the ends of the pressure roll and adapted to be projected through said roll opening into position to be engaged by the successive plates to align the same immediately prior to their engagement by the printing and pressure rolls, and in which the machine also includes means for supporting and elevating a plurality of stacked plates into position to be transferred to the graining mechanism; feeding apparatus for the plates comprising a conveyor for supplying the plates in successive order to said graining mechanism, stop members associated with the conveyor and movable into the path of travel of the plates to align the plates and momentarily arrest their movement toward the graining mechanism, vacuum means movable into engagement with the successive plates for transferring them onto said conveyor, said machine including an endless conveyor running below the transfer roll for supporting and moving the plates beyond said rolls, and means associated with said conveyor to prevent tilting of the plates during their movement.

11. In a machine for applying graining to metal surfaces such as plates, sheets, or the like, including graining mechanism adapted to contact opposite faces of successive plates delivered thereto to apply graining to one of the faces, in which said mechanism comprises transfer, printing and pressure rolls, the pressure roll having a longitudinal opening in its periphery and a movable stop member carried by the pressure roll and adapted to be projected through said roll opening into position to be engaged by the successive plates to align the same immediately prior to their engagement by the printing and pressure rolls, and in which the machine also includes means for supporting and elevating a plurality of stacked plates into position to be transferred to the graining mecha-

nism; feeding apparatus for the plates comprising a conveyor for supplying the plates in successive order to said graining mechanism, oscillatable hook-like stop members associated with the conveyor and movable into the path of travel of the plates to align the plates and momentarily arrest their movement toward the graining mechanism, and suction cups movable into engagement with the successive plates at the top of the stack for transferring them onto said conveyor.

12. In a machine for applying graining to metal surfaces such as plates, sheets, or the like, including graining mechanism adapted to contact opposite faces of successive sheets delivered thereto to apply graining to one of the faces, in which the machine also includes lift mechanism for elevating a plurality of stacked plates into position to be transferred to the graining mechanism, power means for elevating the lift and plate stack, and means engageable by the plates during their transfer from the stack to a conveyor for periodically operating the power mechanism to elevate the lift to position and maintain the succeeding top plates of the stack at a predetermined level, and in which the machine includes manually operable means for lowering the lift when the stack of plates is depleted; feeding apparatus for the plates comprising a conveyor for feeding the plates in successive order to said graining mechanism, automatically controlled vacuum means movable into engagement with the successive plates at the top of the stack for transferring the plates successively onto said conveyor, and valve means automatically operable at predetermined times to break the vacuum and release a plate onto said conveyor.

13. In a machine for applying graining to metal surfaces such as plates, sheets, or the like, comprising graining mechanism adapted to contact opposite faces of successive sheets delivered thereto to apply graining to one of the faces, in which the machine also includes lift mechanism for elevating a plurality of stacked plates into position to be transferred to the graining mechanism, power means for elevating the lift and plate stack, and means engageable by the plates during their transfer from the stack to a conveyor for periodically operating the power mechanism to elevate the lift to position and maintain the succeeding top plates of the stack at a predetermined level; feeding apparatus for the plates comprising a conveyor for feeding the plates in successive order to said graining mechanism, automatically controlled vacuum means movable into engagement with the successive plates at the top of the stack for transferring the plates successively onto said conveyor, means located above the top plate of the stack for engaging the side edges of the plate being removed therefrom to flex the same and thereby ensure its release from the next plate subjacent thereof, and valve means automatically operable at predetermined times to break the vacuum and release a plate onto said conveyor.

14. In a machine for applying graining to metal surfaces such as plates, sheets, or the like, including graining mechanism adapted to contact opposite faces of successive plates delivered thereto to apply graining to at least one of the faces, in which the graining mechanism includes movable stop means for successive plates and in which the machine also includes means

for supporting and elevating a plurality of stacked plates into position to be transferred to the graining mechanism; feeding apparatus for the plates comprising a conveyor for supplying the plates in successive order to said graining mechanism, vacuum means movable into engagement with the successive plates for transferring them onto said conveyor, means for directing a blast of air onto the plates removed from the top of the stack, and stop members associated with the conveyor and movable into the path of travel of the plates to momentarily arrest their movement toward the graining mechanism.

15. In a machine for applying graining to metal surfaces such as plates, sheets, or the like, including graining mechanism adapted to contact opposite faces of successive plates delivered thereto to apply graining to one of the faces, said mechanism comprising transfer, printing and pressure rolls, the pressure roll having a longitudinal opening in its periphery, in which the mechanism also includes means for supporting and elevating a plurality of stacked plates into position to be transferred to the graining mechanism; feeding apparatus for the plates comprising a conveyor for supplying the plates in successive order to said graining mechanism, vacuum means movable into engagement with the successive plates for transferring them onto said conveyor, and means for directing a plurality of air blasts onto the plates as they are removed from the stack, said machine including an endless conveyor for supporting and moving the plates beyond said rolls, and also including means associated with said conveyor to prevent tilting of the plates during their movement.

16. In a machine for applying graining to metal surfaces such as plates, sheets, or the like, including graining mechanism adapted to contact opposite faces of successive sheets delivered thereto to apply graining to one of the faces and transfer, printing and pressure rolls and a movable stop carried by the pressure roll for engagement with the lead edges of successive plates for aligning the plates with relation to the rolls immediately preceding their engagement by the printing roll, in which the machine also includes lift mechanism for elevating a plurality of stacked plates into position to be transferred to the graining mechanism, power means for elevating the lift and plate stack, and means engageable by the plates during their transfer from the stack to a conveyor for periodically operating the power mechanism to elevate the lift and position the top plate of the stack at a predetermined level; feeding apparatus for the plates comprising a conveyor for feeding the plates in successive order to said graining mechanism, automatically controlled vacuum means movable into engagement with the successive plates at the top of the stack for transferring the plates successively onto said conveyor, means for directing a blast of air onto the plates removed from the top of the stack, valve means automatically operable at predetermined times to break the vacuum and release a plate onto said conveyor, and automatically operated means associated with the conveyor and adapted to contact the successive plates for aligning the same prior to their engagement with the graining mechanism of the machine.

HERBERT J. PATTISON.
